(57) **CLAIM**

The ornamental design for a straight adapter for 3" RV sewer hose, as shown and described.

DESCRIPTION

FIG. 1 is an isometric view of a straight adapter for 3" RV sewer hose according to the invention;

FIG. 2 is a top, rear right perspective view according to the invention;

FIG. 3 is a front elevational view according to the invention;

FIG. 4 is a rear elevational view according to the invention;

FIG. 5 is a top plan view according to the invention;

FIG. 6 is a bottom plan view according to the invention;

FIG. 7 is a right elevational view according to the invention; and,

FIG. 8 is a left elevational view according to the invention.
